E. F. MURPHY

SLEEP INDUCING PILLOW

Filed May 4, 1927

INVENTOR
BY *Edward F. Murphy*
John H. Pachell
ATTORNEY

UNITED STATES PATENT OFFICE.

EDWARD F. MURPHY, OF NEWBURGH, NEW YORK.

SLEEP-INDUCING PILLOW.

Application filed May 4, 1927. Serial No. 188,628.

This invention relates generally to pillows for sleeping purposes, and has more particular reference to an aromatic pocket to be sewn on the surface thereof.

5 The invention has for an object the provision of an aromatic pocket for the surfaces of regular pillows for the purpose of inducing sleep to the users thereof.

10 The invention has for a further object the provision of an aromatic pocket for the surfaces of pillows, which can be manufactured and sold at a reasonable cost.

15 For further comprehension of the invention and of the objects and advantages thereof, reference will be had to the following description and accompanying drawings, and to the appended claims in which the various novel features of the invention are more particularly set forth.

20 Referring to the accompanying drawing forming a material part of this disclosure:

Fig. 1 is a face view of a pillow having the invention applied thereto.

25 Fig. 2 is an enlarged fragmentary view of Fig. 1 with a certain part broken away, disclosing another interior part.

Fig. 3 is a vertical sectional view taken on the line 3—3 of Fig. 2.

30 Fig. 4 is a face view of a pillow constructed according to a modification of the invention.

Fig. 5 is a fragmentary vertical sectional view, taken on the line 5—5 of Fig. 4, certain parts not being shown in section.

35 The reference numeral 10 indicates generally a pillow of common construction, and having a pocket 11 secured thereto, by means of stitches 12. The pocket is made of any light material sufficiently porous to allow fragrance from certain substances therein to escape freely, and is sewn on the surface of the pillow a little above the middle and a little to the left, near where the nose of a person sleeping on his right side would rest. The softness of the pillow is, of course, in no way affected 40 if the pocket is properly placed.

45 The pocket 11 is provided with a flap 13 engageable with a button 14 projecting through a buttonhole 15 in the flap and the button being attached to one side of the pocket as at 16. Attached to the side 16 of the pocket is a brush body 17 having projecting bristles 18 abutting against the inside of the flap 13, the flap being thus held by a spring 19 engaged beneath the button 14.

These bristles allow easy passage for the referred to fragrance from the interior to the exterior of the pocket.

The fragrances are given off by aromatics 20, preferably pine needles and sweet grass, enclosed by a cheese cloth bag 21 placed in the pocket 11. The pine needles keep their fragrance indefinitely, but sweet grass grows fainter, and the cheese cloth bag 21 with the aromatics may be refreshed as needed. Mingling chopped sweet grass with the pine needles does not tend to affect the softness 45 of the pillow, and the faint sweet fragrance of the grass suggests cool, refreshing country country spots, which tends to soothe one's tired head and nerves, aiding sleep.

50 Referring in particular to Figs. 4 and 5, a modification has been illustrated, disclosing spaced cloth strips 23 attached at their ends by stitches 24 to the pillow 10. The pocket 11 has a spring 25 fastened to its back side, and this spring is engageable beneath the strips 23, while end straps 26 from the pocket 11 are engageable over the ends of the spring 25 to hold the spring against displacement. The user of the pillow may 55 disengage the ends of the straps 26 from the ends of the spring 25, and remove the spring 25 with attached pocket 11 from the particular strips 23, replacing on other strips 23 to a more comfortable position.

55 While I have illustrated and described the preferred form, construction, and arrangement of the several elements employed, it will be understood that the device is nevertheless, susceptible of considerable modification 60 therein, and I therefore reserve the right and privilege of resorting to all such changes as may be fairly embodied within the spirit and scope of the invention as claimed.

Having thus described my invention, what 65 I claim as new and desire to secure by United States Letters Patent is:

1. An aromatic pocket for attachment on the surface of a pillow comprising a pocket with a flap, a button engaged through the 70 flap and secured to the pocket, a brush back attached to the pocket, bristles therefrom abutting the inside of the flap, and a spring engaged beneath the button, and holding the flap against the bristles.

75 2. A holder for aromatics for attachment on the surface of a pillow comprising a pocket having an open extremity, a flap associated

with said pocket for closing the open extremity thereof, and a spacing member mounted on the side of said pocket comprising a plurality of bristles disposed substantially perpendicular to said flap and to the side of said pocket for retaining the former in spaced relation to the side of said pocket.

3. A holder for aromatics for attachment on the surface of a pillow comprising a pocket 10 having an open extremity, a flap associated with said pocket for closing the open extremity thereof, a spacing member comprising a plurality of bristles disposed substantially perpendicular to the side of said pocket 15 adapted to engage said flap for retaining the same in spaced relation to the side of said pocket when said flap is closed, means mounted on said pocket side adapted to engage said flap for retaining the same closed

and a spring member mounted on said flap 20 adapted to hold the same against said bristles.

4. A holder for aromatics for attachment on the surface of a pillow comprising a pocket having an open extremity, a flap associated with said pocket for closing said open extremity, aromatic substance disposed in said pocket, and a spacing member mounted on the side of said pocket comprising a plurality of outwardly disposed bristles for retaining said flap in spaced relation to the side 30 of said pocket to permit escapement of fragrance from within said pocket through the space between said flap and the side of said pocket.

In testimony whereof I have affixed my 35 signature:

EDWARD F. MURPHY.
